Inventor.

UNITED STATES PATENT OFFICE.

JOHN W. WHEELOCK, OF ALBANY, NEW YORK.

SAD-IRON HOLDER.

SPECIFICATION forming part of Letters Patent No. 274,157, dated March 20, 1883.

Application filed October 20, 1882. (Model.)

To all whom it may concern:

Be it known that I, JOHN W. WHEELOCK, a citizen of the United States, and a resident of the city of Albany, in the county of Albany and State of New York, have invented a new and Improved Device for Use with Flat-Irons, of which the following is a specification.

My invention relates to an improved device for use with flat-irons, in which a flat-iron holder provided with guarded sides and an open-work bottom is made in solid connection with a pad-holder provided with a detachable cleaning-pad, all of which will be hereinafter fully described.

The objects of my invention are, first, to provide a device consisting of a single piece of metal having a flat-iron holder and a cleaning-pad holder, in which said pad-holder will be situated rearward of said flat-iron holder, and guards will bound the sides of both in a continuous manner, with a dividing-guard separating one from the other, whereby the flat-iron will be held in the forward part of the device and the cleaning-pad will be held immovable in the rear portion of the same, so that both the flat-iron holder and the cleaning-pad will be each in a situation for convenient transfer from one to the other of the flat-iron without an actual lifting of the same; second, to provide with a perforated or open-work bottom a floor of a flat-iron holder with three or more upwardly-projecting points or surfaces, which are adapted to hold a flat-iron supported above said bottom, and side guards and a rear guard which will retain said flat-iron in place on said supporting-points, whereby a tipping of the said flat-iron will be prevented, so that a uniform ventilating-space between the lower surface of the same and the top surface of the floor of the holder will be maintained by the united operation of said guards and supporting-points, in and through which air will freely circulate for cooling to a degree the space between the holder and the table or board beneath; third, to so combine and arrange with a flat-iron holder and a cleaning-pad holder situated rearward of said flat-iron holder, and having guards which are continuous and solid with the respective said holders, a cleaning-pad which will be held immovable at the rear of said flat-iron holder, with the plane of its upper surface or side

above the plane of the upper edges of said guards, whereby the flat-iron will be readily transferred from the holder to the cleaning-pad, and the reverse, and permit the bottom of the flat-iron to be moved in any direction over the top surface of the cleaning-pad without its touching the upper edges of the said guards, so that all portions of the bottom of the flat-iron may be cleaned by said pad; fourth, to provide means by which a scraping-blade will be held in convenient situation at the rear end of a device in which its forward portion will be adapted to hold a flat-iron and its rear portion adapted to hold a cleaning-pad, whereby said scraping-blade will be held in situation so as not to become heated by the heat of the flat-iron in its holder; fifth, to produce for a device for use with a flat-iron a cleaning-pad which will be adapted to be readily secured in place with the said device and be formed by the combination, with a metallic pad-table having serrated flange-edges, of a cloth which will engage with said flanges and be strained over the top of the same when turned downward; and, sixth, to combine with a pad-holder means by which a detachable cleaning-pad composed of metal and cloth will be readily secured in place in the holder, and be adapted to be readily removed therefrom for the renewal of the cloth, as may be required. I attain these objects by means of the pieces, parts, or elements illustrated in the accompanying drawings, in which—

Figure 1 represents a perspective view of my improved device. Fig. 2 is a longitudinal sectional elevation of the same with the cloth covering of the cleaning-pad removed. Fig. 3 is a cross-sectional elevation taken at line No. 1 in Fig. 2. Fig. 4 is a cross-sectional elevation taken at line No. 2 in Fig. 2. Fig. 5 is a perspective view of the cleaning-pad table from its lower side, and Fig. 6 is a perspective view of the scraping-blade adapted to enter the receptacle provided at the rear end of the cleaning-pad.

The same letters of reference indicate like parts throughout the several views.

In the drawings, A represents the flat-iron holder proper, and B the cleaning-pad holder, made in solid connection with the former, and shown to be situated at the rear of the same, although, if preferred, it may be situated at

one of its sides. The said flat-iron holder is made with a size and shape and conformation of outer sides which will correspond with the size and shape of the flat-iron to be held, and 5 consists of the perforated or open work bottom, a , and side guards, a' , and rear guard, a^2 , which guards project upward above the upper surface of said bottom and bound the side and rear edges of the same, as shown.

10 Projecting a short distance—say about one-sixteenth of an inch—above the plane of the upper surface of bottom a are supporting points or surfaces $e e$, three or more, properly distributed, which are to operate as points for 15 the support of the bottom of the flat-iron at a plane slightly above the plane of the upper surface of the bottom of said holder, whereby a ventilating space or chamber will be made to intervene between the top surface of the 20 bottom of the holder and the bottom surface of the flat-iron, and this ventilation will be stimulated by the movements of currents of air upward through the perforations in bottom a to the shallow chamber between said bottom 25 and the lower surface of the flat-iron, and thence upward between the sides and ends of the flat-iron and the guards, so that an excessively-heated iron will have its temperature sooner and evenly reduced while being held 30 on the holder than it would be without means for ventilation.

The pad-holder B is made to be a rearward extension of the device from flat-iron holder A, and is formed by the continuation of guards 35 a' rearward past rear guards, a^2 , of the flat-iron holder to a distance of about four inches, more or less, and the end bar, a^4 , made in solid connection with said rearwardly-extended side guards, as shown in Fig. 1. Made with the 40 rear side of guard a^2 is a short horizontal flange, b , and extending from side to side between said extended side guards, and in solid connection with the same, is the cross supporting-bar b' . Running parallel with the said extended guards and from ledge or flange b to cross-bar b' are the horizontal bars $b^3 b^3$, setting inward at a short distance from said side guards, so as to form slots $e e$ between, as shown in Fig. 3. The said pad-holder, being 45 thus formed, is adapted to receive a detachable pad. The rear end bar, a^4 , is extended down to the full depth of the device from the plane of the upper edge of the guards to the plane of the surface on which the device is supported, 50 and has made in its upper side edge a finger-notch, d . A short horizontal flange, d' , is made at the lower edge of bar a^4 , and is made to project inwardly to form the bottom of a receptacle for receiving a scraping-blade, C, Figs. 55 1, 2, and 6, which receptacle is formed between rear end bar, a^4 , and the rear end of the cleaning-pad, D. (Shown by full and dotted lines in Figs. 1 and 2.)

The scraping-blade C is provided with a finger-nail slit, by which, through notch d in rear bar, a^4 , the operator may readily lift said blade out from its receptacle C' when it is desired to

clear the bottom of the flat-iron from any adhering starch or other substance. Projecting horizontally outward from the rear end bar, a^4 , 70 is a lug, f , provided with screw-hole g , by which a screw will be made to hold the device secured to an ironing-board or a table, so as to be prevented from being moved when the operator is moving the flat-iron backward and 75 forward over the cleaning-pad to polish the face of the iron. The forward end of the device is provided with lug f' , provided with screw-hole g' , also for securing said end to the board or table. Intermediate feet, h , projecting downward from the lower side of the bottom of the device, are also provided for supporting the middle portion of the same.

The cleaning-pad D is formed by the sheet-metal table k and the felt or cloth covering l . 80 The table k is made of thin sheet metal, preferably of tin or sheet-iron, and when formed is provided with flanges m , having teeth or serrations $n n$. The said flanges, including the teeth, are made about one-half of an inch deep 85 and stand about at right angles with the lower side of the table proper. The table is made with a length from front to rear edges about one-eighth of an inch less than the distance between rear guard, a^2 , and rear bar, a^4 , so as 90 to form an opening to scraping-blade receptacle C'. The felt or cloth covering l is folded over the top side of table k , with its two opposite side edge portions drawn over and on the points of teeth m and made to engage with 95 the same. The side flanges, m , with the cloth folded against the same, are then slitted at point z , which will correspond with the distance of bar b' from the rear side of receptacle C', and the portion m' is turned down flat against 100 the lower side of the said table, as shown in Fig. 5. The pad, being thus formed, is placed in the pad-holder B, with the angular serrated flanges dropping into the slots $e e$, formed between side guards, $a' a'$, and bars $b^3 b^3$, as shown 105 in Fig. 3, when the serrated edges are bent inward against the lower sides of bars $b^3 b^3$, as shown in the same figure. When the said cleaning-pad is thus secured in holder B its upper cloth surface will be on or slightly above the 110 plane of the upper edge of guards a' and a^2 , so that the bottom of the flat-iron will not be liable to have contact with the edges of said guards when the pad is being operated with for cleaning the bottom of the iron. By bending back 115 the serrated edges of the pad-table the pad will be readily removed, and new felt or cloth covering may be made to replace an old and worn-out one whenever required.

By my improvements the flat-iron will be 120 held from sliding off from its holder, and should the operator place the iron not fairly on the bottom the guards will cant the iron inward, so that all liability of its sliding off will be removed. With the device secured permanently 125 to an ironing-board, the operator will have the device in convenient situation for use, and its attachment will not in the least prevent a skirt or other article of raiment from being placed 130

properly on the board and shifted at will, while at the same time the device will present for successive use the flat-iron holder for temporary reception of the flat-iron while shifting the articles being ironed, the cleaning-pad for cleaning and polishing the face of the iron, and the scraping-blade in its receptacle for ready removal and use for cleaning starch or other substance from the face of the iron.

10 Having described my invention, what I claim, and desire to secure by Letters Patent, is—

1. A device for use with flat-iron, consisting of holder A, adapted to receive a flat-iron, and holder B, adapted to receive a cleaning-pad,

15 said pad-holder being situated rearward of said flat-iron holder and separated by guard a², and both having side guards which are made continuous with each other and extended from the front to the rear of the device on both sides 20 thereof, with all said parts composing a unitary whole, substantially as set forth.

2. In a device for use with a flat-iron, the flat-iron holder A, having an open-work or perforated bottom, which is provided with three 25 or more upwardly-projecting points or supports, which are adapted to support a flat-iron above the top surface of said bottom, and provided with side and rear guards, which will retain the flat-iron in place on said supporting-points, 30 substantially as and for the purpose set forth.

3. With a device for use with a flat-iron, and having its forward portion forming a flat-iron holder and its rearward portion a cleaning-pad holder, and provided with side guards 35 which are made in solid connection with each said holder and continuous from front to rear of said device, and dividing guard separating each said holder from the other, the combination and arrangement of a cleaning-pad, which

is removable and held in said pad-holder with 40 the plane of its upper surface or cleaning side above the plane of the top edges of said guards, substantially as and for the purpose set forth.

4. In a device for use with flat-irons, having holder A, adapted to receive and hold a flat-iron, and cleaning-pad D, situated at the rear of said flat-iron holder, of receptacle C', situated at the rear of said pad and between its rear edge and rear end bar of the device, and having a finger-notch for access to the side of 45 said receptacle for the removal of a scraping-blade therein, all substantially as and for the purpose set forth.

5. The combination, with sheet-metal pad-table k, provided with two oppositely-located 55 side flanges, m, having serrations or teeth n, made with thin lower edges, of pad-cloth l, covering said table and having its opposite end portions engaging with said teeth, substantially as and for the purpose set forth. 60

6. In a device for use with a flat-iron, and having flat-iron holder A and cleaning-pad holder B, situated rearward of the former and provided with bars b³, made with the opposite sides of said pad-holder, with an opening between each said bars and the sides of the same, of the detachable pad D, composed of cloth or equivalent material and fixed to a metal table or piece, provided with teeth or serrations which are adapted to hold said cloth to the 70 said metallic table, and also bind said pad in place in said holder by bending down said teeth on said bars b³, substantially as and for the purpose set forth.
